UNITED STATES PATENT OFFICE.

CHARLES A. MORSE, OF LEOMINSTER, MASSACHUSETTS.

MANUFACTURE OF EXPLOSIVE COMPOUNDS.

SPECIFICATION forming part of Letters Patent No. 236,714, dated January 18, 1881.

Application filed September 17, 1880. (No specimens.)

To all whom it may concern:

Be it known that I, CHARLES A. MORSE, of Leominster, in the county of Worcester and State of Massachusetts, have invented an Improvement in the Manufacture of Explosive Compounds, of which the following is a specification.

I am aware that nitro-glycerine has been mixed with nitro-cellulose to form a gelatinous mass, and that in an English patent to H. E. Newton, No. 4,178 of 1875, (a communication from A. Nobel,) the use of nitrated collodion cellulose is claimed for thickening nitro-glycerine and nitrate of methyl into a gelatinous mass. My invention, however, has reference to the conversion of nitro-glycerine incorporated with nitrates or equivalent oxidizing substance into a solid, hard, dry mass to form an explosive which is capable of being granulated or pulverized, and which can be handled and transported with safety, and is free from the injurious effects and dangerous properties of nitro-glycerine, and which, further, cannot be exploded by heat or fire while in an unconfined state, but is easily exploded when confined by the use of a fulminate-cap, such as is used in exploding ordinary dynamite compounds.

In the different dynamite compounds now and heretofore manufactured, in which nitro-glycerine is mixed with non-explosive and incombustible earths, the nitro-glycerine being only in an absorbed condition, and the explosive force being dependent wholly upon the amount of nitro-glycerine therein contained, the absorbents must necessarily contain a large amount of that explosive substance or they are extremely difficult to explode, and are therefore practically useless, and there is always a liability of the nitro-glycerine leaking out under the varying temperatures of climate to which they are exposed, and thus becoming nearly, if not quite, as dangerous as liquid nitro-glycerine itself. Further, explosives in which mealed gunpowder or other analogous substances are used as the absorbents for the nitro-glycerine are extremely dangerous to handle on account of their low igniting-point and consequent liability to explode from a spark, friction, heat, or concussion. In my improved compound all of these defects are entirely overcome; and my object is to produce a substance

which shall lack all of the above objectionable qualities, and yet shall be equal to the best of them in exploding qualities.

In order to enable others skilled in the art to which my invention appertains to make and use this solidified nitro-glycerine compound, I will proceed to describe my method of preparing the same.

I dissolve common yellow rosin or colophony, or its equivalent resin or gum-resin, such as gumi copal, shellac, or sandarac, in sufficient methyl alcohol, common alcohol, chloroform, ether, or other equivalent solvent capable of dissolving both the resin and nitro-glycerine to effect a complete solution (preferring the ordinary methyl alcohol or wood spirit as being the cheapest) either in the cold or by aid of heat obtained by a water-bath heated to about 120° Fahrenheit. To this solution when cold—that is, when reduced to the ordinary temperature of the air—I add an amount of nitro-glycerine equivalent to about one-half of the weight of the resin dissolved and a quantity of an alkaline or metallic nitrate or chlorate, or equivalent substance, equal to about three times the weight of the resin, and introduce this mixture into a distilling apparatus provided with stirrers.

The temperature of the distilling-vessel is raised by means of a water-jacket or exterior hot material sufficiently to volatilize the alcoholic or other solvent. In the case of methyl alcohol the distilling temperature to evaporate need not exceed 150° Fahrenheit. It is desirable, too, for economy to connect the distilling-vessel with a suitable condenser to collect the solvent for repeated use.

During the process of distilling the stirrers are set in motion in order to break down the mass, so that it may be discharged from the vessel in a more or less pulverized form.

Other methods of granulation may be used if it is not desirable to save the solvent for further use—as, for instance, by stirring the drying-mixture with a wooden rake or by rubbing it through a sieve with a stiff brush. In general, however, it will be found more economical and equally as effective to arrange for the distillation and collection of the solvent by some of the devices well known to the arts for that purpose.

I do not confine myself to the exact proportions of nitro-glycerine, resin, and nitrates, or its equivalent, yet I prefer about the proportions above stated.

- 5 By this process I produce a perfectly homogeneous mixture of nitro-glycerine, resinous substance, and nitrate, chlorate, or other equivalent material which can be handled and transported with perfect safety, and which is free
 10 from the injurious effects of pure nitro-glycerine. By the incorporation or mixing of the nitro-glycerine and resin with the varying proportions of oxidizing agents, such as the alkaline or metallic nitrates or chlorates, as set
 15 forth, an explosive of the grade required may be formed.
- I have found it best to add the alkaline or metallic nitrates or chlorates (in the proper proportions to oxidize the hydrogen, and more
 20 or less completely, according to the application intended, the carbon of the resinous matter, such proportions being easily calculated by the ordinary stoichiometrical rules) to the dissolved resinous matter and nitro-glycerine before evaporating off the solvent. By operating in this way I obtain a more intimate mixture of the ingredients than can be obtained otherwise, while at the same time the salts employed are infilmed with the resinous matter
 25 30 in such a way that they are impervious to the action of water. This is peculiarly advantageous when the salt or salts employed are more or less hygroscopic.
- If desired, a mixture of several oxidizing agents may be added instead of a single substance.

A good formula to manufacture my improved explosive from would be as follows: To ten parts, by weight, of nitro-glycerine add
 35 40 twenty parts of methyl alcohol, twenty-two

parts of resin, and sixty-eight parts of niter, or equivalent oxidizing agents.

I do not claim the incorporation of the nitro-glycerine with a resinous substance by means of a common solvent, broadly, as that forms 45 subject-matter of another pending application.

Having now described my invention, what I claim as new, and desire to secure by Letters Patent, is—

1. The herein-described process of manufacturing an explosive compound, consisting in dissolving nitro-glycerine and a resinous substance in a common solvent, then in intimately mixing them with niter or other oxidizing substance, and then in evaporating off the solvent, 55 substantially as described.

2. The herein-described process of manufacturing an explosive compound, consisting in dissolving nitro-glycerine and a resinous substance in a common solvent, then in incorporating the mass with niter or other oxidizing substance and reducing the mixture to a state of dryness and granulation, substantially as described.

3. An explosive compound, consisting of an 65 intimate solidified mixture of nitro-glycerine, resinous substance, and oxidizing agents, substantially as described.

4. An explosive compound composed of nitro-glycerine and resinous substance mixed 70 or incorporated with niter, the whole being reduced to a solid condition, substantially as described.

In testimony of which invention I hereunto set my hand.

CHARLES A. MORSE.
